CLAIM

The ornamental design for a hanger for weight rack, as shown and described.

DESCRIPTION

FIG. 1 is a top, front, left perspective view of a hanger for weight rack showing my new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines immediately adjacent to the shaded area define the bounds of the claimed design and form no part thereof. The broken lines depicting the remainder of the hanger for weight rack show features that form no part of the claimed design.
